UNITED STATES PATENT OFFICE.

GEORGE KEYSER, OF PHILADELPHIA, PENNSYLVANIA, ASSIGNOR OF ONE-HALF TO
JOHN W. HEPWORTH, OF PHILADELPHIA, PENNSYLVANIA.

MACHINE FOR UNITING LOOPED FABRICS.

Application filed December 20, 1922. Serial No. 607,957.

To all whom it may concern:

Be it known that I, GEORGE KEYSER, a citizen of the United States, residing at Philadelphia, in the county of Philadelphia and State of Pennsylvania, have invented certain new and useful Improvements in Machines for Unitting Looped Fabrics, of which the following is a specification.

- This invention relates to improvements in machines for uniting looped fabrics commonly known as "loopers" wherein are employed a revoluble ring provided with radially projecting impaling pins for carrying the fabrics to be united in combination with a sewing mechanism having a needle and a looper operating in harmony with the revolving ring of impaling pins to produce stitches uniting the loops of fabric carried by the pins.
- 10 A machine of this general character is shown and described in my previous Patent No. 1,069,336, dated August 5, 1913, and my present invention aims to improve the mechanism therein shown and described.
- 15 The objects of my present invention are: first, to provide a novel mechanism for revolving the ring of impaling pins continuously instead of intermittently during the sewing operation; second, to provide a novel means for reciprocating the needle and the looper laterally during the oscillations of the needle radially of the impaling pins to cause the needle to follow the line of travel of the fabrics being united while the needle
- 20 is in the loops thereof, whereby the needle will be in accurate registry with the impaling pin moving beneath the same at all times while the needle is either in the loops of fabric carried by the pin or in engagement with the pin, and whereby the needle and the looper will be carried laterally by a common support which preserves their operative relationship under all circumstances and irrespective of the gage of the distances
- 25 between the impaling pins being employed; third, to provide a novel means for preserving the relationship between the needle and the looper and the tensioning and take up devices for supplying thread thereto in a machine in which the needle has a combined lateral and oscillatory movement; fourth, to provide a novel and advantageous means to connect and disconnect parts of the actuating mechanism for the ring of impaling pins to permit the ring to be turned

independently of its driving connection with the main driving shaft of the machine; and, fifth, to provide a novel means for yieldingly supporting the presser member for the fabrics being united and for supporting the stitch finger around which the stitches are formed for the maintenance of a more desirable relationship between the finger and the loops of fabric for the production of more uniform sewing.

With the foregoing and related objects in view, the invention consists in the novel construction, combination and arrangement of parts hereinafter described and claimed.

In the accompanying drawings, illustrating the invention,

Figure 1 is a plan view of a machine for sewing looped fabrics, embodying my invention.

Figure 2 is a vertical section through the sewing mechanism thereof, on line 2-2 of Fig. 1.

Figure 3 is a vertical section through a part of the sewing mechanism, on line 3-3 of Fig. 2.

Figure 4 is a vertical section through the eccentric and adjuncts for operating the looper.

Figure 5 is a vertical section through the parts shown in Fig. 4, on line 5-5 of Fig. 4.

Figure 6 is a vertical section through parts of the sewing mechanism, on line 6-6 of Fig. 2.

Figure 7 is a plan view of a portion of the ring of impaling pins, a portion of the presser member and the stitch carrying finger carried by the presser member.

Figure 8 is a vertical section through a portion of the mechanism for actuating the ring of impaling pins, on line 8-8 of Fig. 1.

Figure 9 is a horizontal section through the mechanism shown in Fig. 8, on line 9-9 of Fig. 8.

Referring to the drawings, the main frame of the machine comprises a bed plate 10, adapted to be secured upon a table or support, and an overhanging arm 11 rising from and extending outwardly from the bed plate.

The main driving shaft 12 is journalled in a bearing 13 formed by the arm 11 and a bearing 14 rising from the bed plate 10. The shaft 12 is provided with a driving pulley 15 and a suitable clutch 16 for con-

necting and disconnecting the pulley and shaft for starting and stopping the operation of the machine.

Secured to the outer end of the arm 11 is 5 a shaft 17 which extends downwardly therefrom and fixedly supports a disc-like head 18.

Surrounding the head 18 and rotatably fitted to the periphery thereof is a ring 19 10 supported by a ring plate 20 which is secured to the bottom of the head 18. The ring 19 is provided with a circular series of radially-projecting impaling pins 21 for receiving the loops of the fabrics to be 15 united and supporting and advancing them to the sewing mechanism hereinafter described.

The ring 19 is provided with internal gear teeth 22 in mesh with a pinion 23 arranged 20 within an opening in one side of the head 18. The pinion 23 is secured to a vertical shaft 24 which is mounted to turn in a bearing 25 in a bracket 25 secured on the head 18.

The upper end portion of the shaft 24 25 has a toothed wheel 26 keyed thereon; and, rotatably mounted on the wheel 26, is a worm wheel 27 which embraces and encloses the toothed wheel 26. The teeth of the wheel 26 correspond in number with the teeth of 30 the worm wheel 27, and the worm wheel 27 has a vertical stem or pin 28 fitted to turn therein and provided on its lower end with a projection 29 forming a pawl adapted to engage any one of the teeth of the wheel 26 35 to cause it to be turned by and with the worm wheel 27. The upper end portion of the stem 28 extends above the worm wheel 27 and is encircled by a spring 30 one end of which engages the worm wheel 27 and the other end of which engages a transverse pin 31 projecting from the stem and tends to 40 turn the pawl into operative engagement with the teeth of the wheel 26. The pawl 29 may be disengaged from the wheel 26 to 45 permit it to be turned independently of the worm wheel 27, for a purpose hereinafter explained, by turning the stem 28 by hand against the action of the spring 30. The shaft 24 extends downwardly below the bottom 50 of the head 18 and it is provided with a suitable handle or crank 32 by means of which the shaft 24 may be operated to turn the impaling pin ring 19 by hand when the pawl 29 is disengaged from the wheel 26. 55 The worm wheel 27 is in mesh with a worm 33 on a supplemental driving shaft 34 fitted to turn in bearing 35 on the bracket 25 and a bearing 36 connected to the bed plate 10. The supplemental shaft 34 is provided with 60 a bevel gear wheel 37 which co-acts with a similar wheel 38 on the main driving shaft 12, whereby, when the driving shaft 12 is rotated, the ring 19 carrying the impaling pins 21 will be slowly and continuously revolved at a uniform speed.

The arm 11 of the main frame of the machine carries a reciprocative support 39 formed by a casting having a cylindrical projection 40 fitted to slide longitudinally in bearing 41 formed by the arm 11. The support 39 is prevented from turning about the axis of the projection 40 by a rod 42 projecting fixedly from the arm 11 parallel to the axis of the projection 40 and through a bearing 43 on the support 39. The support 39 is slideable on the rod 42 and its projection 40 is slideable in the bearing 41 and it is guided thereby in a manner to permit it to be reciprocated back and forth as will be presently explained.

The support 39 has a shaft 44 fixed thereto and extending therefrom and carrying a head 45 which is located beneath the supplemental driving shaft 34. The head 45 is provided with a post 46 carrying a bearing plate 47 having side flanges 48 embracing the post and pivoted thereto by a pin 49 which extends through the post 46 and flanges 48. The plate 47 rests against an adjusting screw 50 screwed into and through the post 46 and it engages a cam 51 on the shaft 34 and is held against the same by a spring 52 encircling the rod 42 between the support 39 and an adjustable head 53 screwed on to the rod 42 and tending to move the support 39 and bearing plate 47 carried thereby toward the frame arm 11. During the rotation of the shaft 34, the cam 51 and spring 52 operate to reciprocate the frame for a purpose hereinafter described.

The curved needle 54 and the curved looper 55 of the sewing mechanism and their supporting and guiding parts are carried bodily by the reciprocative support 39, and the needle and the looper are moved relatively to each other while being thus bodily reciprocated.

The needle 54 is carried by an arm 56 projecting from a collar 57 on a shaft 58 which is arranged parallel to the main driving shaft 12 and which is mounted to turn in the support 39, as clearly shown in the drawings. The needle 54 and shaft 58 are located with respect to the impaling pins 21 passing beneath them so that when the arm 56 is oscillated the needle 54 will be projected and retracted in a manner to cause its pointed free end portion to be projected over the impaling pins and through the grooves therein and through the loops of the fabrics carried thereby and to be retracted therefrom during the sewing operation. The collar 57 is provided with a projecting arm 59 having a crank pin 60 extending therefrom parallel to the shafts 12 and 58. The pin 60 is fitted to turn in one end of an arm 61 whose other end is provided with a strap 62 surrounding an eccentric 63 on the main driving shaft 12, whereby, when the shaft 12 is rotated, the

needle arm 56 will be oscillated. The connecting arm 61 slides in a vertical slot 64 in a bracket 65 which is connected to and supported by the frame arm 11 to maintain the arm 61 at right angles to the driving shaft 12 and prevent it from being moved laterally by the support 39. During the reciprocations of the support 39 and the lateral movements of the needle actuating arms 56 and 59 and pin 60 therewith, the pin 60 slides longitudinally in the opening in the connecting arm 61.

The looper 55 is carried by an arm 66 projecting from the lower end of a vertical shaft 67 which is mounted to turn in a bearing formed by the support 39. The looper 55 is positioned to move over the loops of the fabrics carried by the impaling pins 21 and to be moved from side to side of the line of travel of the loops and to co-operate with the needle 54 to effect the sewing operation when the shaft 67 is rocked and the looper 55 is thereby oscillated. The shaft 67 is rocked to oscillate the arm 66 by an eccentric 68 on the driving shaft 12, and this eccentric 68 is connected to the shaft 67 as follows: The upper end portion of the shaft 67 is provided with a horizontally projecting arm 69 having an upwardly extending post 70 on the outer end thereof. The upper end of the post terminates in a ball 71 which is fitted to a socket in one end portion of a connecting arm 72. The other end portion of the arm 72 is connected to a strap 73 which surrounds the eccentric 68.

The periphery of the eccentric 68 is made convex and the inner surface of the strap 73 is made concave and fitted to the convex surface of the eccentric to permit the arm 72 to be rocked laterally, and to permit the post 70 to describe an arc at right angles to the plane of rotation of the eccentric 68 and thus permit the back and forth rocking of the shaft 67 and also permit its back and forth bodily movement by the reciprocative frame 39. The eccentric strap 73 is retained in place upon the eccentric 68 by a ball 74 arranged in oppositely adjacent grooves 75 and 76 in the eccentric 68 and strap 73, respectively; and the ball 74 is maintained in place on a line extending at right angles to the axis of the arm 72 from the center of the eccentric 68 by its engagement with a spring 77 arranged within a depression in the strap 73.

The reciprocal support 39 carries tension, take up and thread guiding devices for the needle thread 78 and the looper thread 79, as follows: The support 39 is provided with an upwardly extending arm 80 having two horizontal rods or pins 81 and 82 extending therethrough and secured thereto. The rod 81 carries two pairs of spring pressed tension discs 83 and 84 of usual construction, and the rod 82 is provided with

two thread guiding eyes 85 and 86 for the needle and looper thread 78 and 79, respectively. The upper end of the arm 80 is provided with two outwardly extending screws 87 carrying two spring take up arms 88 and 89 of usual construction for the needle and looper threads 78 and 79, respectively; and the support 39 is provided with projections having thread guiding eyes 90 and 91 for guiding the threads 78 and 79 from the take up arms 88 and 89 to the needle 54 and looper 55, respectively.

The needle and looper threads 78 and 79 are drawn from a suitable source of supply to and through the eyes 85 and 86, thence down between the tension discs of the pairs thereof 83 and 84 and under the rod 81 and up to and through the eyes in the take up arms 88 and 89, thence down to and through the eyes 90 and 91, and thence to and through suitable grooves in the needle and looper arms 56 and 66 to the eyes of the needle and looper 54 and 55, respectively.

A horizontally extending presser member 92 is provided beneath the impaling pins 21 forming a passage between it and the ring 19 for guiding the fabrics to be united and properly positioning them on the impaling pins, as they approach and meet the needle 54 and looper 55. The member 92 has a projection 93 formed thereon which narrows the passage between the member 92 and ring 19 in the region beneath the needle 54 and which is adapted to engage the fabrics being sewed. The member 92 is secured to the lower end of a vertical stem 94 which extends upwardly and through a bearing in the arm 11. The stem 94 is fitted to turn and slide longitudinally in its bearing, and the upper end portion thereof extends above the top of the arm 11 and has a head 95 fixed thereon. Encircling the stem 94 between the arm 11 and head 95 is a spring 96 one end of which extends into an opening in the head 95 and the other end of which extends into an opening in the arm 11. The spring 96 acts to hold the top surface of the member 92 yielding up against the bottom of the impaling pins 21 and also to turn the stem 94 and press the projection 93 of the member 92 inwardly against the fabrics carried by the pins 21, for purposes hereinafter explained.

The spring pressed member 92 carries a stitch receiving finger 97 to cause the needle and looper to form loose or elastic stitches in uniting fabrics and to permit them to form a chain of stitches when no fabrics are being sewed, so that the sewing of the fabrics will commence immediately upon the presentation thereof to the needle and looper. The stitch receiving finger 97 is formed by and projects from the horizontal portion of a bent plate 98 which has a vertical portion 99 resting within a vertical

120
125
130

guiding groove in the outer portion of the member 92. The vertical portion 99 of the plate 98 has a vertical slot therein for the reception of a set screw 100 screwed into the member 92 to hold the plate 98 and stitch finger 97 in different positions of vertical adjustment. The stitch receiving finger 97 is arranged above the inner edge portion of the projection 93 and over and parallel to the path of the edges of the fabrics carried by the impaling pins 21 and the free end portion of the finger 97 projects over the path of the needle 54 and beyond the same in the direction of movement of the fabrics carried by the pins 21, whereby, during the sewing operation, stitches will be formed around the finger 97 and discharged from the free end thereof with or without the presence of the fabrics at the sewing point. When the needle 54 penetrates the edges of the fabrics being sewed it tends to move the fabrics radially outward on the impaling pins 21 and maintain them in close relation to the edge of the projection 93 of the member 92 which serves as a stop or abutment, and, I have discovered that by having the finger 97 bear a fixed relation to the projection 93 and by permitting the finger 97 and projection 93 as a unit to yield outwardly against the spring 96 when the thickness of the edges of the fabrics being united varies, I am enabled to produce stitches having a marked degree of superiority as regards uniformity and evenness irrespective of such variations in the edges of the fabrics.

The operation of the machine is as follows:

When power is applied to the driving shaft 12 the ring 19 and the impaling pins 21 carrying the loops of the edges of the fabrics to be united are revolved continuously and at a uniform rate of speed in the direction of the arrow in Fig. 1; and the needle 54 and looper 55 are oscillated by the eccentrics 63 and 68, respectively.

Each time the main driving shaft 12 and therewith the supplemental driving shaft 24 makes one complete revolution, the ring 19 is advanced a distance equal to the distance between two adjacent impaling pins 21; and each time the shaft 12 makes a complete revolution, the needle 54 and the looper 55 are each advanced and retracted to form a stitch by the oscillations of their carrying arms 56 and 66, respectively. An impaling pin 21 is thus presented to the needle 54 for each stitch forming operation.

During the formation of the stitches the needle 54 passes beneath the stitch receiving finger 97 and through the grooves in the impaling pins 21 and through the loops of the fabrics carried by the impaling pins, and the looper 55 passes back and forth over

the finger 97 and the loops of the fabrics carried by the pins 21; and the needle and looper are arranged and operated relatively to each other so that the needle 54 will take a loop of looper thread 79 from the looper 79 on one side of the edges of the fabrics and the looper 55 will take a loop of needle thread 78 from the needle on the other side of the edges of the fabrics and thereby form a chain of stitches around the finger 97 and through the loops of the fabrics while the fabrics are passing the sewing point, and form a chain of stitches around the finger 97 alone when no fabrics are present.

The needle 54 and looper 55 co-operate to form the stitches substantially in the same manner as the needle and looper shown and described in my previous Patent No. 1,069,-336, co-operate to form stitches.

As the needle 54 is operated to produce stitches during the continuous movement of the impaling pins 21, the cam 51 moves the needle 54 laterally against the action of the spring 52 at the speed and in the direction of movement of the impaling pins 21 passing beneath the same while the needle is actually engaged with the impaling pin or while it is being projected through and being withdrawn from the loops of the fabrics carried by the pin. This occurs during about two-thirds of the cycle of operation of the needle. During the remaining one-third of the cycle, and while the needle is clear of the impaling pins, the spring 52 is occupied in moving the needle 54 laterally in the reverse direction to meet the next succeeding impaling pin 21. It will thus be understood that the needle 54 will be moved back and forth laterally to meet and move with the impaling pins successively as they pass beneath the needle. The contour of the cam 51 is such that the needle 54 will be moved slowly in the direction of movement of the impaling pins in accurate registry therewith while working within the groove in one of the pins, and will be moved quickly back or in the reverse direction to meet the next succeeding pin, during the relatively short time that the needle 54 is clear of the impaling pins.

The long portion *a* of the cam 51 moves the needle in the direction of movement of the pins 21 and the short portion *b* of the cam 51 permits the spring 52 to return the needle 54 to meet the next succeeding pin 21.

Should any knots be present in the loops of fabrics impaled upon the pins 21, or should the fabrics carried by the pins be of uneven thickness, the presser member 92 will yield outwardly against the action of the spring 96 to accommodate the variations in the fabrics and permit them to pass between the ring 19 and the projection 93 without disturbing the relation of the finger 97 to the projection 93, resulting in the produc-

tion of elastic stitches and of the uniform sewing previously referred to.

Should any parts of the fabrics being united become jammed between the impaling pins 21 and the presser member 92, the latter may be readily depressed by hand against the action of the spring 96 to free the jammed parts.

When it is desired to turn the ring 19 carrying the impaling pins 21 backwardly or forwardly relatively to the needle 54 for any desired purpose without operating the sewing mechanism, the same may be done by disengaging the pawl 29 from the wheel 26 and operating the crank 32 to turn the shaft 24 by hand with the needle 54 in a position retracted from the impaling pins 21.

It will be observed that the worm 33 makes one complete revolution for each back and forth lateral movement of the needle and that the same part of the worm 33 operates the worm wheel 27 to move the impaling pins forwardly during each time that the needle is moving laterally with the pins, and that another but always the same part of the worm 33 operates the worm wheel 27 to move the pins 21 forwardly during the backward or reverse lateral movement of the needle 54. It will also be observed that this relationship between the needle 54 and the worm 33 is preserved irrespective of the number of times that the shaft 24 is disconnected from and turned relatively to the worm wheel 27 for turning the ring 19 without operating the sewing mechanism.

I have discovered that the preservation of this relationship between the needle 54 and the worm 33 is important in preserving the accurate registry of the needle 54 with the pins 21 and their proper co-operation during the stitch forming operations, particularly after some wear has occurred in the operating parts of the machine.

45 I claim as my invention:

1. In a machine for uniting looped fabrics, the combination of a supporting frame, a ring provided with impaling pins for carrying the fabrics to be united, means to revolve said ring continuously, a reciprocative support, a sewing needle carried by the support and movable thereon, a looper carried by the support and movable thereon, means to move the needle and the looper relatively to each other and to the support carrying them to produce stitches, and means to reciprocate the support laterally of the impaling pins passing the needle during the stitch producing operations and to cause the needle to meet and move in registry with an impaling pin at each reciprocation of the support, causing the needle and the looper to follow the line of travel of the fabric when the needle is in the loops thereof.

60 2. In a machine for uniting looped fabrics,

the combination of a supporting frame, a ring provided with impaling pins for carrying the fabrics to be united, means to revolve said ring continuously, a reciprocative support, a sewing needle carried by the support and movable thereon, a looper carried by the support and movable thereon, means to move the needle and the looper relatively to each other and to the support carrying them to produce stitches, and means to reciprocate the support laterally of the impaling pins passing the needle during the stitch producing operations and to cause the needle to meet and move in registry with an impaling pin at each reciprocation of the support, causing the needle and the looper to follow the line of travel of the fabric when the needle is in the loops thereof, the last named means comprising a rotatable cam, a part connected to the support and engaging the cam, and a spring holding said part against said cam.

3. In a machine for uniting looped fabrics, the combination of a supporting frame, a ring provided with impaling pins for carrying the fabrics to be united, a driving shaft journaled in the frame, a second shaft extending substantially at right angles to the driving shaft and geared thereto, means to revolve said ring continuously, a reciprocative support, a sewing needle carried by the support and movable thereon, a looper carried by the support and movable thereon, means actuated by the driving shaft to move the needle and the looper relatively to each other and to the support carrying them to produce stitches, and means actuated by said second shaft to reciprocate the support laterally of the impaling pins passing the needle during the stitch producing operations, causing the needle and the looper to follow the line of travel of the fabric when the needle is in the loops thereof.

4. In a machine for uniting looped fabrics, the combination of a supporting frame, a ring provided with impaling pins for carrying the fabrics to be united, a driving shaft journaled in the frame, a second shaft extending substantially at right angles to the driving shaft and geared thereto, means actuated by said second shaft to revolve said ring continuously, a reciprocative support, a sewing needle carried by the support and movable thereon, a looper carried by the support and movable thereon, means actuated by the driving shaft to move the needle and the looper relatively to each other and to the support carrying them to produce stitches, a cam carried by said second shaft, a part connected to the support and engaging the cam, and a spring holding said part against the cam, said cam and spring reciprocating the support laterally of the impaling pins passing the needle during the stitch producing operations, causing the

needle and the looper to follow the line of travel of the fabric when the needle is in the loops thereof.

5. In a machine for uniting looped fabrics, the combination with a supporting frame, a ring provided with impaling pins for carrying the fabrics to be united, a driving shaft journaled in the frame, a second shaft extending substantially at right angles to the driving shaft and geared thereto, and means actuated by said second shaft to revolve said ring continuously, of a sewing mechanism including a reciprocative support, a sewing needle carried by the support and movable thereon, means actuated by the driving shaft for operating the needle, and means actuated by said second shaft to reciprocate the support laterally of the impaling pins passing the needle during the operation thereof, causing the needle to follow the line of travel of the fabric when the needle is in the loops thereof.

6. In a machine for uniting looped fabrics, the combination with a supporting frame, a ring provided with impaling pins for carrying the fabrics to be united, a driving shaft journaled in the frame, a second shaft extending substantially at right angles to the driving shaft and geared thereto, and means actuated by said second shaft to revolve said ring continuously, of a sewing mechanism including a reciprocative support, a sewing needle carried by the support and movable thereon, means actuated by the driving shaft for operating the needle, a cam carried by said second shaft, a part connected to the support and engaging the cam, and a spring holding said part against the cam, said cam and spring reciprocating the support laterally of the impaling pins passing the needle during the operation thereof, causing the needle to follow the line of travel of the fabric when the needle is in the loops thereof.

45. 7. In a machine for uniting looped fabrics, the combination of a supporting frame, a ring provided with impaling pins for carrying the fabrics to be united, means to revolve said ring continuously, a reciprocative support, a sewing needle carried by the support and movable thereon, a looper carried by the support and movable thereon, means to move the needle and the looper relatively to each other and to the support carrying them to produce stitches, means to reciprocate the support laterally of the impaling pins passing the needle during the stitch producing operations, causing the needle and the looper to follow the line of travel of the fabric when the needle is in the loops thereof, and means including tension devices carried by the support for guiding threads to the needle and to the looper.

8. In a machine for uniting looped fabrics, the combination of a supporting frame,

a driving shaft journaled in the frame, a ring provided with impaling pins for carrying the fabrics to be united, means including a co-operating worm and worm wheel actuated by the driving shaft to revolve said ring, and sewing mechanism provided with a needle and means actuated by the driving shaft for projecting and retracting the needle and to reciprocate it laterally to meet and move in registry with an impaling pin at each reciprocation of the needle, said ring operating means also including a device to connect and disconnect it from said ring without disturbing the relationship between the needle operating means and the worm and its worm wheel.

9. In a machine for uniting looped fabrics, the combination of a supporting frame, a driving shaft journaled in the frame, a ring provided with impaling pins for carrying the fabrics to be united, a worm actuated by the driving shaft, a worm wheel actuated by the worm, gearing operatively connected to said ring and provided with means to connect it to and disconnect it from the worm wheel at will, and sewing mechanism provided with a needle and means actuated by the driving shaft for projecting and retracting the needle and to reciprocate it laterally to meet and move in registry with an impaling pin at each reciprocation of the needle.

10. In a machine for uniting looped fabrics, the combination of a supporting frame, a driving shaft journaled in the frame, a ring provided with impaling pins for carrying the fabrics to be united, a worm actuated by the driving shaft, a worm wheel actuated by the worm, a supplemental shaft geared to said ring, means comprising a toothed wheel and a pawl to connect and disconnect the supplemental shaft and worm wheel at will, and sewing mechanism provided with a needle and means actuated by the driving shaft for projecting and retracting the needle and to reciprocate it laterally to meet and move in registry with an impaling pin at each reciprocation of the needle.

11. In a machine for uniting looped fabrics, the combination of a supporting frame, a driving shaft journaled in the frame, a ring provided with impaling pins for carrying the fabrics to be united, a supplemental shaft geared to said ring, a toothed wheel fixed on the supplemental shaft, a worm wheel mounted to turn on the axis of the supplemental shaft, a pawl carried by the worm wheel and operable to connect and disconnect the worm wheel and the toothed wheel, and a worm actuated by the driving shaft and in operative engagement with the worm wheel, and sewing mechanism provided with a needle and means actuated by the driving shaft for operating the needle

in harmony with the operation of the impaling pins.

12. In a machine for uniting looped fabrics, the combination of a supporting frame, a driving shaft journaled in the frame, a ring provided with impaling pins for carrying the fabrics to be united, a driving wheel, means actuated by the driving shaft for turning said wheel, a supplemental shaft 10 geared to said ring, means comprising a toothed wheel and a pawl to connect and disconnect the supplemental shaft and driving wheel at will, and sewing mechanism provided with a needle and means actuated 15 by the driving shaft for projecting and retracting the needle and to reciprocate it laterally to meet and move in registry with an impaling pin at each reciprocation of the needle.
13. In a machine for uniting looped fabrics, the combination of a supporting frame, a driving shaft journaled in the frame, a ring provided with impaling pins for carrying the fabrics to be united, a supplemental 20 shaft geared to said ring, a toothed wheel fixed on the supplemental shaft, a driving wheel mounted to turn on the supplemental shaft, means actuated by the driving shaft for rotating said driving wheel, a pawl carried by the driving wheel and operable to connect and disconnect the driving wheel and the toothed wheel, and sewing mechanism provided with a needle and means actuated by the driving shaft for operating 25 the needle in harmony with the operation of the impaling pins.

14. In a machine for uniting looped fabrics, the combination with a supporting frame, a ring provided with impaling pins for carrying the fabrics to be united, means to revolve the ring, and sewing mechanism co-operating with the pins for uniting the fabrics, of a movable presser member beneath the path of travel of the impaling pins and forming the outer wall of a passage for the fabrics between the member and the ring, means to press the member 40 yieldingly toward the ring, and a stitch finger around which the sewing mechanism forms its stitches, said finger being carried by and movable with said member.

15. In a machine for uniting looped fabrics, the combination with a supporting frame, a ring provided with impaling pins for carrying the fabrics to be united, means to revolve the ring, and sewing mechanism co-operating with the pins for uniting the fabrics, of a movable presser member beneath the path of travel of the impaling pins and forming the outer wall of a passage for the fabrics between the member and the ring, and means to press the member yieldingly toward the ring and also to press it yieldingly toward the pins.

16. In a machine for uniting looped fab-

rics, the combination with a supporting frame, a ring provided with impaling pins for carrying the fabrics to be united, means to revolve the ring, and sewing mechanism co-operating with the pins for uniting the fabrics, of a movable presser member beneath the path of travel of the impaling pins and forming the outer wall of a passage for the fabrics between the member and the ring, means to press the member yieldingly toward the ring and also to press it yieldingly toward the pins, and a stitch finger around which the sewing mechanism forms its stitches, said finger being carried by and movable with said member.

17. In a machine for uniting looped fabrics, the combination with a supporting frame, a ring provided with impaling pins for carrying the fabrics to be united, means to revolve the ring, and sewing mechanism co-operating with the pins for uniting the fabrics, of a movable presser member beneath the path of travel of the impaling pins and forming the outer wall of a passage for the fabrics between the member and the ring, a stem carrying said member and mounted to turn in said frame to permit the member to move toward and from the ring and mounted to slide in said frame to permit the member to move toward and from the pins, and means to press the member yieldingly toward the ring and also to press it yieldingly toward the pins.

18. In a machine for uniting looped fabrics, the combination with a supporting frame, a ring provided with impaling pins for carrying the fabrics to be united, means to revolve the ring, and sewing mechanism co-operating with the pins for uniting the fabrics, of a movable presser member beneath the path of travel of the impaling pins and forming the outer wall of a passage for the fabrics between the member and the ring, a stem carrying said member and mounted to turn in said frame to permit the member to move toward and from the ring and mounted to slide in said frame to permit the member to move toward and from the pins, means to press the member yieldingly toward the ring and also to press it yieldingly toward the pins, and a stitch finger around which the sewing mechanism forms its stitches, said finger being carried by and movable with said member.

19. In a machine for uniting fabrics, the combination of a continuously rotating dial having a ring of impaling pins, a curved thread needle, an arm for said needle, means for oscillating said arm, a looper, a looper support, means for oscillating the looper and its support in a plane at an angle to the plane of oscillation of said needle, a common support for both the needle arm and the looper support, and means for moving said common support laterally during

- the oscillatory movement of the needle whereby the needle is carried laterally while in the loops to correspond with the movement of the subjacent impaling pins.
- 5 20. In a machine for uniting fabrics, the combination of a dial having a ring of impaling pins, means for continuously rotating the dial, a bracket, a support for said bracket upon which it is longitudinally movable, a 10 driving shaft, a rotatable cam driven from said shaft, a connection between said cam and the bracket for moving the latter on its support from the cam, a thread needle carried by said bracket, means for oscillat- ing the needle on said bracket, a looper support on said bracket, a looper on said support, means for oscillating said looper and its support in a plane at an angle to the plane of movement of said needle, said bracket moving laterally during the oscillation of the needle whereby the latter is carried laterally while in the loops to correspond with the movement of the subjacent impaling pins.
- 5 20 In testimony whereof I affix my signature hereto.

GEORGE KEYSER.
